UNITED STATES PATENT OFFICE.

PEARL H. BRAINARD, OF MACOMB, ILLINOIS, ASSIGNOR TO MACOMB MANUFACTURING COMPANY, OF MACOMB, ILLINOIS, A CORPORATION OF ILLINOIS.

HEAT-INSULATED CONTAINER.

Application filed October 13, 1923. Serial No. 668,291.

To all whom it may concern:

Be it known that I, PEARL H. BRAINARD, a citizen of the United States, residing at Macomb, in the county of McDonough and State of Illinois, have invented certain new and useful Improvements in Heat-Insulated Containers, of which the following is a specification.

This invention relates to containers having walls constructed with special reference to resistance to heat transfer from the exterior to the interior of the container, or vice versa, and particularly to containers the walls of which comprise inner and outer shells positioned to leave a space between them, and having this space especially treated to check the transfer of heat by either conduction or convection, namely, by converting it into a substantial jacket of low heat conductivity through means of a filling, such, for instance, as subdivided cork; the inner shell being designed to constitute a receptacle for materials to be protected against change in temperature; and the outer shell serving as the confining and protecting skin for the subdivided material of the insulating jacket, as well as a mounting and centering means for the inner shell during packing of the insulating material between the shells which are united over the restricted area afforded by concentric necks with which the two shells are formed.

The embodiment of the invention herein selected for purposes of illustration is designed primarily to serve as a portable container for liquid or other foods, but it is to be understood that the novel features of the invention are applicable to containers designed with forms and dimensions that render them available for a wide variety of other purposes, such, for instance, as stationary water coolers, refrigerators, incubators, and, in short, all containers in which it is desirable to minimize the conduction of heat through the walls.

The object of the invention is to provide an improved method of packing the subdivided material between the inner and outer shells of a double walled container of the kind herein described, whereby the material can be introduced with greater convenience and accuracy, and be more densely packed, particularly under the bottom of the container, and thereby better adapted to resist

downward displacement of the inner shell 55 relatively to the outer shell in response to external shock. Accordingly, another feature of the invention consists in forming an outer shell with the bottom portion thereof originally separated in about the horizontal 60 plane of the bottom of the inner shell, assembling the inner shell with the body of the outer shell, with their necks concentric, molding a body of cement into the space between the necks in adhering relation to the 65 highly porous material of the inner neck, and in filling relation to reentrant spaces or recesses in the outer neck, then filling the space between the inner shell and the body 70 of the outer shell with subdivided insulating material, for instance, ground cork, ramming said material firmly in position to adapt it to check air circulation which might result in convection of heat, and better serve as a spacing medium to fix the inner shell 75 against vibration in the outer shell, and then, when the space between the shells up to the level defined by the existing side wall of the outer shell is completely packed, heaping upon the upwardly presented bottom of 80 the inner shell a pyramid of subdivided insulating material in a quantity determined by the natural angle of repose of such material when piled thereon, and finally pressing into position upon the top of such pyramid 85 of subdivided material, and into telescoping relation with the side walls of the outer shell, the flanged bottom of the outer shell in a manner to trap such a substantial volume of the insulating material between the 90 bottoms of the inner and outer shells and in the remaining side space as will complete the insulating jacket with the density desired, and establish in that portion of the insulating jacket substantially the same conditions that were attained by ramming the insulating material into the space between the inner shell and the portion of the outer shell first assembled therewith.

To contribute to the trapping of the 100 requisite body of subdivided material between the two bottoms, the bottom of the inner shell is preferably slightly concaved, and the depth of the flange upon the bottom of the outer shell, which enters into telescoping relation with the side walls of the outer shell, is such as to meet the side walls materially in advance of the ultimate position of

the bottom and thereby trap the insulating material against escape, while compression due to pressing the bottom home is taking place.

5 The invention will be fully understood upon reference to the accompanying drawings, in which—

10 Figure 1 shows in vertical longitudinal section, and in an inverted position, a water bottle embodying the several features of the invention, and

15 Figure 2 is a similar view illustrating the method of assembling the bottom of the shell and insuring desired density of the filling material around the bottom.

20 1 represents the inner shell, 2 the outer shell positioned one within the other with a substantial space between them, and 3 represents a filling of ground cork or other material of low heat conductivity filling said space. The shells 1 and 2 are constructed, respectively, with necks 1^a, 2^a, located with a substantial space between them, and this space is filled with a body 4 of hard setting cement, the necks being provided, respectively, with grooves 1^b and 2^b to firmly key this body of cement between them. Preferably the neck 2^a will have an inturned flange 2^c for determining the axial relation 25 between the inner and outer shells, and this, together with the necks 1^a and 2^a, constitutes a mold in which the uniting body 4 of cement can be conveniently and accurately cast when the assembled shells of the 30 container are placed in inverted position, with the bottom section of the outer shell omitted and before the insulating filler 3 is put in place.

35 The body 4 of cement is preferably built up to a level slightly above the shoulder of the outer shell, as shown, as this insures a solid body of cement and permits the cement to be introduced in a relatively slack condition in which it can flow intimately into all 40 the spaces. The material of which the inner shell 1 is constructed is particularly advantageous in securing a solid and immovable union between the necks of the shells by the cement filler 4, as the cement 45 adheres very much more intimately with the surface of the inner shell by reason of its non-glazed porous condition. The cement used for uniting the inner and outer shells is preferably a good grade of Portland cement, or equivalent material, with a sufficient proportion of plaster of Paris to neutralize any acid condition of the cement, or preferably hydrated lime in sufficient proportion for this purpose, or equivalent 50 alkaline matter, as this will lend the additional advantage of rendering the cement union still less pervious to moisture.

55 In the neck union there is a firm anchorage of the inner shell in the outer container 60 which fixes these two members against relative axial movement, and the firm packing of the insulating material between them completes the means for positioning the inner shell within the outer shell.

65 In order to secure the proper distribution and desired density of insulating material between the inner and outer shells, it is quite easy to pack the annular space between the sides of these members before the bottom member 2^y is put in position. But considerable difficulty is experience in securing proper density of packing between said bottom member of the inner shell and the bottom of the outer shell. These parts are assembled, according to the present invention, 70 by first developing a pyramid or pile of subdivided insulating material upon the upturned bottom of the shell 1, the side walls of the shell as thus far assembled extending upward preferably to about the level of 75 said bottom, and then pressing the bottom section 2^y of the shell downward upon this cone of material and until the telescoping flange 2^c of said bottom section fits within the annular side wall of the outer shell, when the subdivided material will have been 80 displaced laterally sufficiently to fill the entire remaining space between the bottom of the inner shell and the bottom of the outer shell, and the material will be rendered particularly compact and firm beneath the bottom because of the flat or slightly 85 concaved form of the bottom of the inner shell which limits the flowing of the subdivided material under the axial pressure of 90 the shell bottom.

95 The procedure last described develops an assembly which is particularly advantageous in a heat insulated container in which the actual physical connection between the inner and outer members is limited to the 100 neck portions thereof.

105 While I have described in detail the preferred embodiment of the several features 110 of my invention, I desire it understood that the terms of the appended claims rather than the detailed description are to be taken as defining the scope of the invention.

I claim:

115 1. A heat insulated container comprising an inner shell, an outer shell spaced from said inner shell, and a packing of subdivided heat insulating material in the space between said shells; the bottom of the inner shell having means constructed to resist outward flowing of the subdivided material; and the subdivided material introduced between said bottom and the bottom of the outer shell being under substantial pressure 120 in a direction perpendicular to the bottom 125 of the inner shell.

130 2. A heat insulated container comprising inner and outer shells with heat insulating material confined between them; the inner shell having a concave bottom, and the outer

shell having a side wall terminating adjacent said concave bottom and a bottom wall engaged with said side wall and pressing the insulating material upon said concave bottom; the mass of material between the bottoms of the shells being normally of largely greater volume than the space into which it is pressed.

3. A heat insulated container comprising inner and outer shells, and heat insulating material in the space between the shells; the inner shell having a bottom which, when presented upwardly, is adapted to support a pile of insulating material in subdivided form and having a specific angle of repose, and the outer shell having a side wall and a flanged bottom, the flange of said outer shell bottom being adapted to engage with the end of said side wall and thereby provide a compartment between the bottoms adapted to compress and hold a body of such insulating material piled upon the inner shell bottom previous to putting the outer shell bottom in place; the end of the outer shell side wall being so spaced from the edge of the inner shell bottom, as to constitute a proper gage for the insulating material when poured upon said inner shell bottom, and insure the volume of such material desired to be compacted within said compartment.

4. The method of assembling the inner and outer shells of double wall heat insulated containers which consists in first introducing into a bottomless outer shell, an inner shell having its bottom constructed with means to resist outward flowing of subdivided packing material placed thereon,

packing the space between the sides of the shells with insulating material, piling in insulating material in subdivided form upon the bottom of the inner shell, in volume substantially greater than the ultimate space to be maintained between the bottoms of the shells and then applying an outer shell bottom with substantial axial pressure and flattening and condensing the pile of material between the two bottoms.

5. The method of assembling the inner and outer shells of heat insulated receptacles which consists in introducing into a bottomless outer shell, an inner shell having its bottom constructed with means to resist outward flow of subdivided insulating material placed thereon, packing insulating material into the space between the sides of the inner shell and the surrounding confine, piling upon the inner shell bottom, insulating material in subdivided form and having a specific angle of repose, the end of the surrounding confine being so positioned relatively to the bottom of the inner shell, as to cause the said side wall to act as a proper gage for insulating material when poured upon the inner shell bottom, thereby insuring the desired volume of such material to be compacted between the bottoms, and finally putting the outer shell bottom in position over such gaged pile of insulating material, pressing said outer bottom axially to the outer shell, and thereby compacting the pile into the space between the bottoms.

Signed at Macomb, Illinois, this 10th day of October, 1923.

PEARL H. BRAINARD.
